EARL W. WITTER AND ARTHUR E. WITTER, OF GYPSUM, OHIO.

ROTARY DRIVING DEVICE.

1,178,564.

Specification of Letters Patent. Patented Apr. 11, 1916.

Application filed November 1, 1912. Serial No. 729,096.

To all whom it may concern:

Be it known that we, EARL W. WITTER and ARTHUR E. WITTER, citizens of the United States, and residing at Gypsum, 5 Ohio, have invented certain new and useful Improvements in Rotary Driving Devices, of which the following is a specification.

Our invention relates to driving devices particularly adapted for use in rotary 10 curry-combs and brushes and has for its object the provision of mechanism of the character mentioned which is simple in construction and efficient in use.

Other objects of the invention will appear more fully hereinafter, the novel features of the invention being set forth distinctly in the claims.

Referring to the accompanying drawings, Figure 1 is an elevational view with a 20 portion of the casing broken away to show the interior mechanism; Fig. 2 is a plan view with portions broken away to show the rotary curry-comb and brush, gearing and the covers for the gearing; Fig. 3 is a 25 detail view of the gear and clutch mechanism at the outer ends of the curry-comb and brush drum; and Fig. 4 is a cross-sectional view on the line 4—4 of Fig. 3 looking in the direction of the arrows, and 30 shows a type of ball clutch that may be used for the purpose hereinafter explained.

In Fig. 1 the numeral 1 designates the casing or the frame of the device, 2 designates a cover or block attached to the upper surface of the casing 1, and 3 designates a strap extending across the top of the device. It is intended that the operator's hand be inserted through the strap 3 so as to secure a good hold on the device. If desired this strap may extend lengthwise on the block 2. In the lower left hand portion of the frame or casing 1 is journaled a traction roller 4 which is covered with some frictional material 5 such as rubber or the like. To the outer ends of the shaft 6 of the roller 4 are rigidly connected the bevel-gears 7, 7'. The bevel-gear 7 meshes with the bevel-gear 8 which is mounted on one end of the shaft 9 near the other end of 45 which is a bevel-gear 10. The shaft 9 is journaled in the bearings 11 and 12 which are fastened by means of the brackets 13 and 14 respectively, to the side of the casing or frame 1 as shown in Fig. 2. The 50 bevel-gear 7' meshes with a bevel-gear 8'

on a shaft 9'. At the end of the shaft 9' opposite the end carrying the gear 8' is another bevel gear 10'. The shaft 9' is journaled in the bearings 11' and 12' which are carried by the brackets 13' and 14' respectively. These brackets are fastened to the other side of the casing 1 as indicated in Fig. 2. The bevel-gear 10 meshes with a bevel-gear 15 and the bevel-gear 10' meshes with the bevel-gear 15'. The bevel-gears 15 and 15' are mounted longitudinally on the ends of the shaft 16, and are held in place by means of the nuts 25 and 25' fitting on screw threaded nuts 26 and against shoulders as shown on the dotted lines of 60 Fig. 3. These bevel-gears 15, 15' are each provided with hubs, 17 and 17' which are journaled in the bearings 18, 18' in casing 1 as shown in Figs. 2 and 3. Extending lengthwise of the shaft 16 is a key 19 by 70 means of which the ends or heads 20, 20' of the drum 21 are connected to rotate with the shaft 16. This key 19 also extends through the sleeve or collar 22 of the clutches located at the ends of the drum 80 near the bevel-gears 15 and 15'. The clutches near the ends of the shaft 16 are reversely arranged and each of them may be constructed as indicated in Figs. 3 and 4. In the lateral recesses 24, 24' are located 85 small loose cylinders or balls 23, 23' which are free to move when released. When the gear 15 is actuated in one direction the hub 17 will rotate freely but when moved in the opposite direction the clutch will become 90 operative to transmit power to the shaft 16 and thereby rotate the same.

The cylindrical portion 21 of the drum or the drum proper carries longitudinally curry combs 27 and brushes 28 which are 95 alternately arranged as shown in Fig. 1. We prefer to have the curry-combs 27 and brushes 28 extend in separate lines over the entire length of the drum, that is, longitudinally on the shaft of the drum. The 100 brushes and curry-combs may however, be arranged spirally but regularly and alternately. The brushes and curry-combs may also be arranged sectionally and in alignment with each other either longitudinal of 105 the drum or spirally thereon.

To the inner wall of one end of the casing 1 is rigidly connected a bracket 29 which extends nearly over the entire width of the casing as indicated in Fig. 2. This 110

bracket 29 carries at its inner end a brush or scraping device 30 and engages the curry-combs 27 and the brushes 28 as shown in Fig. 1, so as to dislodge the material which is carried up with such curry-combs 27 and brushes 28. In order to more fully effect the cleaning of the curry-combs 27 and brushes 28 another scraping brush or cleaning device 33 may be located at the opposite side of the rotary drum 21. The second cleaning device comprises a bracket 31 which is secured rigidly to the partition 32 inside of the casing or frame 1. The bracket 31 and the scraping device or brush 33 carried at the inner end thereof extends longitudinally of the drum 21 and preferably extends a short distance beyond the same at each end as shown in Fig. 2. The brush 33 is located similarly to the brush 30 with respect to the curry-combs 27 and brushes 28, that is, in the path of the movement of the latter. The curry-combs 27 are preferably of metal and the brushes 28 of bristle, but the cleaning brushes 30 and 33 are preferably of wire, but may be of bristle if desired.

The material that is scraped by means of the brushes 30 and 33 from the curry-combs 27 and brushes 28 is collected automatically in the pans 34, 34' which are respectively hinged at 35, 35' to the casing or main frame of the device. The lateral ends of these pans engage the said walls of the casing which determines the position of the pans when closed position as shown in Fig. 1. However, if desired, the right angle extensions 36 and 36' may be relied on to limit the upward movement of the pans 34, 34'. The pans 34, 34' are connected at 37, 37' to the springs 38 and 38' the other ends of which are connected respectively at 39, 39' to the partition 32 and one of the end walls of the casting 1. These springs hold the pans in closed position or when open move them back to closed position. The pans are also provided with flanges or retaining members 40 and 40' which extend longitudinally of the drum and prevent the materials collected in the pans from flowing out when the entire device is tilted to various inclinations.

To the end of the casing 1 which is opposite the end to which the roller 4 is journaled are connected the brackets 41, 41' each of which carries a sliding block 42 mounted in the guide ways 43 for vertical up and down movement. A spring 44 in each of the brackets 41 and 41' tends to hold the sliding blocks 42 in their lowermost positions. The sliding blocks 42 of the bearings for the shaft 45 which carries an idler cylinder 46 as shown in Fig. 2. This idler cylinder extends approximately over the entire width of the rear portion of the casing 1. It is evident that when the strap

3 is grasped and the roller 4 is moved over the surface of the cleaned varying pressure on the block 2 will regulate the amount of pressure of the curry-combs 27 and brushes 28. The greater the pressure on the block 2 by means of the operator's hand, particularly at the rear portion of the casing 1, the more the springs 44 will be compressed. This permits the rear end of the casing to descend closer to the surface being cleaned and therefore the drum 41 also brushes nearer the said surface. This will effect the greater pressure on the curry-combs and the brushes on the surface being cleaned, whenever necessary. But whenever desired only a slight or medium amount of pressure may be brought to bear when the rollers 4 and 46 are simply rolled over said surface.

In order to protect the gearing and prevent dust and hair from collecting in same the covers 47 and 47' are provided. These covers may be made of separate pieces of metal attached to the lateral faces of the casing 1, but if desired may be made partly or wholly integral therewith.

The shaft 9 is mounted on an inclination with respect to the surface of the casing to which it is connected. The shaft 9' is similarly arranged. This is for the purpose of providing a larger gear 10 or 10' at the end of the shaft 9 or 9' than the gear 8 or 8' at the other end of such shaft. This inclination of the shafts 9 and 9' effects the increase of the ratio of the gearing so that the drum 21 will rotate several times more than the roller 4 for any given interval. For instance if the roller 4 rotates once and the gearing is such that the shaft 9 will rotate once during such period, the drum 21 may be rotated about 4 times for the same period. When the inclination of the shafts is undesirable the said shaft may be mounted on brackets of the same size so as to occupy symmetrical positions, that is, lie longitudinally of the casing and at equal distance therefrom. It is evident that in such arrangement the gear 8 and 10 can be of the same size but the gear 15 of smaller size or even of the same size. The gear 7 however, must be made of larger size, than the other gears so as to obtain an increased speed of rotation of the drum 21. If the gear 7 is of such size that for one rotation thereof the gear 8 will rotate four times the drum 21 would also rotate 4 times even if the gears 10 and 15 are of the same size as the gear 8. We, therefore, do not wish to be limited to the inclined shafts. These are shown in the drawings to more forcibly illustrate the speed of rotation of the drum 21 with respect to the roller 4.

The operation of the apparatus hereinbefore described will now be explained. When the cross strap 3 is grasped by the operator and the roller 4 is moved over a

horse's back the frictional covering 5 will effect the rotation of the gears 7, 7'. If the roller 4 occupies a position near the horse's head and the device is moved in a direction away from the horse's head, the roller 4 will be given a rotation in a clockwise direction. The gears will all be actuated, but only one set will be effective in transmitting motion to the drum 21 because the clutches near the ends of the shaft 16 are reversely arranged and only one of them can be effective to rotate the drum 21. The drum 21 is to be rotated always in the same direction. This can be done by one set of gears at one side of the device by substituting a direct connection for the clutch connection. When the roller 4 is moved in a clockwise direction away from the head of the horse the gears 7', 8', 10' and 15' are actuated and the gear 15' is given an anti-clockwise direction of movement. The clutch within the hub 17' should therefore engage the shaft 16 to rotate the same in the direction of the arrow *a* as indicated in Fig. 1. The clutch at the other end of the shaft 16 in the hub 17 should at this time be free and it will be noticed that the gear 10 is arranged on the other side of the gear 15 with respect to the arrangement of the gears 10' and 15'. Therefore, the shafts 9 and 9' are of different lengths. When the roller 4 is moved in a clockwise direction the gear 15 is also in a clockwise direction, but if the clutch within the hub 17 operated at this time the drum 21 would be rotated in the wrong direction. When the roller 4 is moved over the horse's back in the opposite direction however, so as to give this roller 4 an anti-clockwise direction of movement the gear 15 would be given an anti-clockwise direction of movement. The clutch within the hub 17 at this time goes on, while the clutch within the hub 17' is free; therefore the drum 21 will be always rotated in the anti-clockwise direction of movement as indicated by the arrow *a* whether the roller 4 is rotated in one direction or the other. As before explained, when greater or less pressure is brought to bear on the block 2 by the operator's hand the springs 44 will be compressed and the curry-combs and brushes will operate with varying effect. The cleaning brushes 30 and 33 by engaging the curry-combs 27 and brushes 28 will scrape off the dust and hair therefrom, which will be collected by the pans 34, 34'. At any time the material collected by the pans may be ejected, and as soon as the pans are released the springs 38 and 38' will return them to their initial or closed positions.

Obviously those skilled in the art may make various changes in the details and arrangement of parts without departing from the spirit and scope of our invention as defined by the claims hereto appended, and we

therefore, do not wish to be restricted to the precise construction herein described and shown in the drawings.

Having thus fully disclosed an embodiment of our invention, what we claim and wish to have protected by Letters Patent of the United States is—

1. In combination, a frame having bearings therein; a shaft extending through said bearings; a clutch member secured to said shaft; a wheel hub rotatably mounted on said clutch member and journaled in one of said bearings, and locking members co-operating with said wheel hub and clutch member to form a driving connection between the hub and shaft. 75

2. In combination, a frame having bearings therein; a shaft extending through said bearings; a wheel hub rotatably mounted on said shaft and journaled in one of said bearings, there being an annular recess at one end of said hub; a clutch member secured to said shaft and disposed in said annular recess; and locking members co-operating with the periphery of said recess and clutch member to provide an operative connection between the hub and shaft. 85 90

3. In combination, a frame; a driving shaft journaled in said frame; a driven shaft journaled in said frame; a beveled gear on each end of each of said shafts; a beveled gear meshing with each of said first mentioned beveled gears; shafts, each carrying two of said second mentioned beveled gears; and clutches operatively connecting the gears on said driven shaft with said driven shaft, said gears and clutches being arranged to cause said driven shaft to be rotated in one direction regardless of the direction of rotation of said driving shaft. 100 105

4. In combination, a frame; a driving shaft journaled in said frame; a driven shaft journaled in said frame and disposed parallel with said driving shaft; intermediate shafts extending between the ends of said driving and driven shafts; meshing beveled gears on the ends of said shafts; and clutches at the ends of said driven shaft co-operating with the gears on the latter to provide driving connections between such driven shaft and the beveled gears on the latter, said beveled gears and said clutches being arranged to cause said driven shaft to rotate in one direction regardless of the direction of rotation of the driving shaft. 110 115

5. In combination, a frame; a driving shaft journaled in the frame with its ends extending through said frame; bevel gears on the extended ends of said shaft; a driven shaft parallel with the driving shaft and extending through the frame; bevel gears rotatively mounted on the extended ends of driven shaft; hubs on the last mentioned gears journaled in the frame; driving connections between the gear on each end of 125 130

the driving shaft and the gear on the corresponding end of the driven shaft; clutch members secured to the driven shaft and extending into said hubs, there being portions 5 of the clutch members at the ends of the hubs journaled in the frame with said hubs; and catches coöperating with the clutch members and hubs.

6. In combination, a frame; a driving 10 shaft journaled in said frame; a driven shaft journaled in said frame and disposed parallel with said driving shaft; intermediate shafts extending between the ends of said driving and driven shafts; meshing bevel 15 gears on the ends of such shafts, the gears on one intermediate shaft meshing with the adjacent sides of the gears on the driving and driven shafts at one side of the frame, and one of the gears on the other intermediate shaft meshing with one of the adjacent 20

sides of the gears on the driving and driven shafts at the other side of the frame and the other of the gears on said other intermediate shaft meshing with one of the remote sides of the gears on the driving and 25 driven shafts at said other side of the frame; and clutches on the driven shaft connecting the latter with the gears thereon and driving the driven shaft in one direction regardless of the direction of rotation of the driving 30 shaft.

In testimony whereof we have signed our names to this specification, in the presence of two subscribing witnesses, on this 26th day of October, A. D. 1912.

EARL W. WITTER.
